UNITED STATES PATENT OFFICE.

HENRY A. OWEN, OF WHITINSVILLE, MASSACHUSETTS, ASSIGNEE TO WHITIN MACHINE WORKS, OF WHITINSVILLE, MASSACHUSETTS, A CORPORATION OF MASSACHUSETTS.

FEELER-MOTION FOR LOOMS.

1,127,086.

Specification of Letters Patent.

Patented Feb. 2, 1915.

Application filed September 1, 1914. Serial No. 859,630.

To all whom it may concern:

Be it known that I, HENRY A. OWEN, a citizen of the United States, residing at Whitinsville, in the county of Worcester, State of Massachusetts, have invented a certain new and useful Improvement in Feeler-Motions for Looms, of which the following is a specification, reference being had thereto in to the accompanying drawings.

My invention dispenses with the differential and other measuring principles heretofore favored in practice. It utilizes the principle of a feeler-member which, directly meeting the supply of weft or filling contained in the working shuttle, and held by the wound mass from transverse displacement so long as such mass contains a sufficiency for present continuation of the weaving, is displaced longitudinally of the shuttle by the contact-pressure when the said supply is exhausted to the predetermined extent.

The invention resides in a feeler-motion in which a feeler-member constructed and arranged to operate as aforesaid, and an actuator operatively combined with said feeler-member, having a reciprocating working stroke and controlled as to its operation through the lateral placement of the said feeler-member, are combined with a controller that is actuated by the normally-directed stroke of the operatively-disposed actuator.

In carrying the invention into practical effect I embody in my improved feeler-motion a number of principles and features of construction providing for a novel mode of operation and improved results.

An illustrative embodiment of the various principles and features of the invention is represented in the drawings, in which latter,

Figure 1 is a plan view of certain portions of a loom with the said embodiment applied thereto, the lay being at back center, and a full supply of weft or filling being contained in the shuttle. Fig. 1^a is a view in vertical section on line 1^a, 1^a, of Fig. 1. Fig. 2, Sheet 2, shows the parts of Fig. 1 in end or side elevation. Fig. 3, Sheet 2, is a plan view of the same parts but with the lay at front center. Fig. 4, Sheet 2, is an

end or side elevation of the parts in the positions occupied by them in Fig. 3. Fig. 5, Sheet 4, is a plan view with the lay at front center, showing the supply of weft or filling nearly exhausted and the parts positioned and acting to indicate automatic weft-replenishing mechanism into action. Fig. 6, Sheet 2, is an end or side elevation of the parts as shown in Fig. 5.

The feeler-member of the illustrated embodiment of the invention is marked 1. As in the case of the feeler-members of other feeler-motions in use, it is supported from the loom-frame in a position in line with an opening or slot 2 (dotted lines) in the front-plate 3 of one of the shuttle-boxes of the lay 4, and is adapted to project through the said opening or slot 2 as the lay swings forward and also through a registering slot 5 (dotted lines) in the front wall of a shuttle 6 that has passed home in the said shuttle-box, so as to receive against its tip or feeling end the pressure of the exterior of the wound mass 7 of weft or filling contained in the said shuttle. Also, as in the case of other feeler-motions, the feeler-member 1 is mounted upon a carrier that is movable from front to rear and vice versa in the loom, and that is normally held with yielding force in a rearward position to present the feeler-member to the said wound mass within the shuttle, and driven forward in the loom by the push of the said mass against the feeler-member. The carrier which I prefer to employ because of its advantages is a horizontal arm or lever, as for instance that shown at 8, pivoted as at 9 upon a convenient support. Such support in this instance is a bracket 10 fixed on top of the breast-beam 11. The carrier 8 is supported by the upper surface of the bracket 10 in manner permitting it to swing in a horizontal plane around the pivot 9. The means of holding the carrier normally in its rearward position consists in this instance in a contracting spiral spring 11^a, the said position being defined by a stop-pin 12 projecting upward from bracket 10. By the action of the said spring the carrier is returned rearward against the stop-pin 12 after each forward movement. While I prefer the swinging carrier-arm or carrier-lever

herein shown, for practical reasons, certain of which are stated hereinafter, other forms and arrangement of carrier are known in the art and may be employed in cases in which it is not deemed necessary to secure the special advantages that are inherent in the swinging arm or lever.

The feeler-member 1 is shown mounted upon a rearward extension of the outer extremity of the carrier-arm or lever. The distance of the feeler-member laterally outward from the pivot 9 is sufficient to cause the tip or feeling end of the feeler-member to travel in an outwardly-convex arc of comparatively slight curvature. The lateral displacement of the feeler-member lengthwise of the shuttle by the contact-pressure when the supply of weft or filling contained within the shuttle is exhausted to the predetermined extent preferably is provided for, as in the drawings, by mounting the feeler-member upon a vertical pivot 13 in connection with the feeler-carrier 8 so that it may swing transversely in a horizontal plane, and by offsetting its tip or weft-engaging portion 1^a laterally with respect to the pivot 13 so that the forwardly-directed push of the filling-mass may take effect upon the feeler-member at one side of the pivot, with a tendency to swing the feeler-member around the pivot. Provision is made for keeping the feeler-member yieldingly in its normal position upon the feeler-carrier. A convenient means for the purpose is the contracting spiral spring 14 having one end thereof engaged with the feeler-member and the other with an outstanding projection 8^a from the feeler-carrier. This spring acts with a tendency to keep the forwardly-extending branch or arm 15 of the feeler-member against a stop-pin 16 rising from the feeler-carrier as in Fig. 1. This stop-pin determines the normal position of the feeler-member upon the feeler-carrier. The extent of the movement of lateral displacement of the feeler-member is defined by a second stop-pin 17, rising from the feeler-carrier at the other side of the branch or arm 15.

The tip or engaging portion of the feeler-member is wedge-shaped, with a blunt edge for contact with the wound mass of weft or filling contained within the shuttle 6. It is given the said shape in order that when the said edge contacts with a mass of weft or filling of any thickness it may engage with the exterior of such mass so as to be held from lateral movement, and that when the said mass has become substantially exhausted the tip or feeling portion may enter at times between the coils or turns and make contact with the surface of the weft-carrier upon which the weft or filling is wound.

When, as in the drawings, the shuttle oc-

cupies the shuttle-box at the side of the loom at which the feeler is located, and the lay moves forward from its position in Figs. 1 and 2 to that in Figs. 3 and 4, so as to carry the shuttle toward the feeler and so that the feeler-member enters slot 5 in the front shuttle-wall, the exterior of the wound mass of weft or filling contained in the shuttle will press against the tip or engaging portion of the feeler-member as in Figs. 3 and 4. The push of the said mass, in consequence of taking effect against the feeler-member at one side of the pivot 13 connecting it with the carrier 1, will tend to cause the feeler-member to swing or swivel around the said pivot as just mentioned. The tendency of the feeler-member to swing or swivel around the said pivot will be opposed by the tension of the spring 14, which however is light and consequently offers only a slight resistance to the swinging or swiveling of the feeler-member, and by the engagement of the tip or engaging portion of the feeler-member with the exterior of the wound mass. The combined resistance will prevent the feeler-member from swinging or swiveling around the said pivot 13. The push applied to the feeler-member by the wound mass of weft or filling will take effect in swinging the carrier-arm or carrier forward by overcoming the resistance offered by the spring 11^a, with the feeler-member in its relative position shown in Figs. 1 and 3 upon the carrier.

I have referred herein to an actuator that is controlled as to its operation through the lateral placement of the feeler-member, and to a controller that is actuated by the normally-directed stroke of the operatively disposed actuator. These may be variously combined and arranged, and the invention is not necessarily restricted with reference to the precise construction, arrangement, and manner in which they are combined. In the illustrated embodiment of the invention the construction and arrangement are such that as the feeler-member in its normal position upon the feeler-carrier is being carried forward the forwardly-extending arm 15 in connection with the feeler-member will clear or miss the adjacent end of a lever 18 that is mounted upon bracket 10 and pivoted thereto at 19, and consequently the position of the lever 18 will not be affected. Lever 18 constitutes in the present instance the so-called controller. It is arranged to control the latch 20 in connection with the mechanism for bringing about the predetermined change in the operation of the loom. The forwardly-extending arm 15 that is combined with the feeler-member constitutes the actuator for the said controller. The actuator is formed integral with the feeler-member in this instance as a matter of con-

venient construction. It is, as will be seen, controlled as to its operation through the lateral placement of the feeler-member. The normal position of the controller-lever 18 is with its outer arm rearward, this position being given to the said lever through the coöperation of a contracting spiral spring 21 which is connected with the inner arm of the lever, and a stop-pin 22 rising from bracket 10, against which stop-pin the spring 21 tends to hold the lever pressed.

The latch 20 is pivotally mounted at 23 upon a link or extension 24 extending rearward from the arm 25 mounted upon the usual breast-beam rockshaft (not shown), the latch and said arm being operatively combined in practice with automatic weft-replenishing mechanism or other mechanism for bringing about a predetermined change in the operation of the loom. The latch is formed at the underside of its rear end with a tooth or shoulder 20^a, Fig. 1^a, designed to be engaged by a striker 26 constituted by a lateral projection from the weft-hammer lever 27. In the present construction the latch is slightly overweighted at the front of its pivot 23 so that normally the latch occupies the horizontal position in which it is shown in Figs. 1^a, 2 and 4, with its lighter rear end in contact with the under side of controller 18 and its tooth or shoulder elevated above the path in which the top of the striker moves.

So long as the portion of the wound mass of weft or filling which is presented to the tip or engaging portion of the feeler-member contains a sufficient thickness the action is as already described; namely, the tendency of the push applied by the said mass to the said tip or engaging portion of the feeler-member to displace the tip or engaging portion transversely outward in the direction of the length of the shuttle is prevented by the hold of the comparatively firm weft or filling upon the tip or engaging portion from thus displacing the feeler-member. Consequently, the actuator misses or clears the controller in each forward stroke of the feeler and actuator, this being represented in Fig. 3, Sheet 3. When, however, the supply of weft or filling within the shuttle is so far depleted as to permit the tip or engaging portion of the feeler-member to make contact with the surface of the bobbin 7^a or other filling-carrier within the shuttle a different action takes place. The push of the said surface against the said tip or engaging portion will deflect the latter laterally outward, so that the feeler-member will be swung or swiveled upon its pivot 13 into the position shown in Fig. 5, Sheet 4, thereby placing the actuator 15 in line with the outer end of the controller 18, and as the feeler-member and its carrier 8 are moved forward the actuator will act against the controller to swing the same. The inner end of the controller will thereby be moved rearward so that it will act upon the cam-shaped portion 20^b of the latch 20 and press 70 down the rear end of the latter so as to swing its tooth or shoulder 20^a into the path of the striker 26. The striker by engagement with the tooth or shoulder as in Fig. 6, Sheet 2, will transmit movement to the arm 75 25 to thereby indicate or call the change in the operation of the loom. To obviate the necessity for timing the weft-hammer with its striker 26 to act in close accord with the beat-up of the lay, I so proportion the 80 weights of the portions of the latch 20 at front and rear, respectively, of pivot 23 that after the latch is tilted its recovery will be sluggish or slow, thus providing that the tooth or shoulder 20^a shall remain down in 85 the path of the striker long enough to afford proper opportunity for the striker to engage with the said tooth or shoulder.

It is intended in the case of the particular feeler-member shown in the drawings that 90 when the wound weft or filling upon the barrel of the bobbin at the point where the tip or feeling portion of the feeler-member engages is reduced to a single layer, as in Fig. 5, the said tip or feeling portion shall 95 penetrate between the coils or turns and make contact with the surface of the bobbin under them. The tendency of the pressure of said surface against the tip or feeling portion to displace the latter laterally outward will cause then the tip or feeling portion to press some of the said coils or turns outward as in Fig. 5, making an opening between them. In case the first contact of the said surface with the tip or feeling portion 100 should not operate to displace the feeler-member the spreading apart of the coils or turns will facilitate the further displacement of the feeler-member, so that on the second or third contact the actuator will be 105 brought into operation. So long as there are at least two cross-wound overlying layers of coils or turns at the place where the feeler-member engages with the wound weft or filling, the crossing of the wind of one 110 layer by that of another will bind the coils or turns together so that the lateral displacement of the feeler-member will be prevented. Hence, constructed as shown in the drawings, the feeler-devices seldom if ever 115 act before the wound weft or filling has been reduced to a single layer. In consequence of the feeler-member being mounted upon the horizontally swinging carrier 1 so that the tip or engaging portion thereof 120 shall travel forward in an outwardly convex arc, the said tip or feeling portion has a compound or combined forward and outward movement. The effect of this is a 125 tendency to cause its end or edge to dip or 130

pick under the coils or turns of yarn next outward beyond the same, so as the more effectually to engage with such coils or turns. This has the double effect of holding the 5 feeler-member with greater certainty from premature lateral displacement outward, and of facilitating the separating of the coils or turns after the weft or filling has become reduced to a single layer.

10 The two levers 8 and 18 are approximately parallel, and swing in unison and substantially in parallelism when the actuator is engaged with the controller 18. The action is, therefore, smooth and easy. In virtue of 15 mounting the feeler-member upon a swinging carrier, there is no tendency to cramping of such carrier in its movements. The action is better than would be the case if it were mounted upon a slide-bar or rod moving 20 in a straight guideway or ways, for the pressure of the forwardly-moving wound mass of weft or filling in the latter instance would tend to cause such slide-bar or rod to cramp in the said guideway or ways. I contemplate employing the slide-bar or rod in 25 some cases, however.

Various changes and modifications in addition to those mentioned herein may be made in the construction and arrangement 30 of the parts.

The lateral offsetting of the tip or feeling portion of the feeler-member is toward the side of the pivot 13 at which the head or base of the filling-carrier in the shuttle is 35 located, in order that the tendency to lateral displacement of the feeler-member may manifest itself in the direction toward the said head or base. The reason for this is that since the weft or filling is wound first 40 in layers of short length at and near the head or base of the filling-carrier there is less tendency to premature displacement of the coils or turns of the first or innermost layer in the said direction when such layers 45 are exposed to being engaged by the tip of the feeler-member than there would be in the direction toward the tip of the filling-carrier.

If preferred, the parts may be combined 50 and arranged in obvious manner so that the controller shall be engaged and moved by the actuator at every feeling action so as to move the latch out of the path of the striker at every beat of the latter until the spent 55 condition of the weft or filling contained in the shuttle results in a failure of the actuator to operate the controller to withdraw the latch from the path of the striker.

I claim as my invention:—

60 1. Loom-feeler devices comprising a feeler directly meeting the supply of weft or filling contained in the shuttle and displaced longitudinally of the shuttle by the contact-pressure when said supply is exhausted to the predetermined extent, an actuator op-

eratively combined with said feeler having a reciprocating working stroke, and a controller which is actuated by the actuator in the normally-directed stroke thereof when the feeler has been laterally displaced. 70

2. Loom-feeler devices comprising a feeler-member receiving directly the push of the supply of weft or filling contained in the shuttle and displaced longitudinally of the shuttle by the contact-pressure when said supply is exhausted to the predetermined extent; a feeler-carrier moved through the said push, a controller, and means for latching the controller to the carrier through such displacement of the feeler-member and thereby actuating the controller through the normally-directed movement of the carrier. 75

3. A feeler-motion for looms comprising a feeler-member that receives directly the push of the wound mass of weft or filling 80 contained in the working shuttle and is moved forward thereby, and that is displaced longitudinally of the shuttle by forward pressure against it when the wound mass is substantially exhausted, an actuator 85 that is controlled as to its operation through the lateral placement of the said feeler-member, and a controller that is actuated by the normally-directed movement of the operatively-disposed actuator. 90

4. A feeler-motion for looms comprising a feeler-member that receives directly the push of the wound mass of weft or filling contained in the working shuttle and is moved forward thereby, and that is displaced longitudinally of the shuttle by the 100 pressure of contact with a surface within the wound mass when given access to such surface by the paying-out of the weft or filling, an actuator that is controlled as to its operation 105 through the said lateral placement of said feeler-member, and a controller that is actuated by the normally-directed movement of the operatively disposed actuator. 95

5. A feeler-motion for looms comprising 110 a contact-member receiving directly the push of the wound mass of weft or filling contained in the working shuttle, held by a sufficiency of such mass for weaving purposes against lateral displacement through the 115 said direct push, and displaced longitudinally of the shuttle by the said push when the wound mass is substantially exhausted, a carrier for said contact-member, moved forward by the push against the contact-member, and a controller actuated through the forward movement of the carrier and contact-member when the latter is operatively disposed. 120

6. A feeler-motion for looms comprising 125 a contact-member receiving directly the push of the wound mass of weft or filling contained in the working shuttle, held by a sufficiency of such mass for weaving purposes against lateral displacement through the 130

- said push, and displaced longitudinally of the shuttle by the pressure of a surface within the wound mass when given access to such surface by the substantial exhaustion of said mass, a carrier for said contact-member, moved forward by the push against the contact-member, and a controller actuated through the forward movement of the carrier and contact-member when the said member is operatively disposed. 10
7. A feeler-motion for looms comprising a feeler-member arranged for displacement lengthwise of the shuttle in addition to movement forward in unison with the lay, and restrained from such displacement through the pressure thereagainst of a plurality of overlying layers of the wound mass of weft or filling contained in the working shuttle, and which penetrates between the coils when a single layer remains and is displaced longitudinally of the shuttle through contact with a surface under the said layer. 15
8. A feeler-motion for looms comprising a feeler-member arranged for movement forward in unison with the lay, having in addition a normal movement longitudinally of the shuttle tending to spread slightly apart the coils of the wound mass of weft or filling between which its engaging portion is entered, and arranged for further displacement lengthwise of the shuttle by the pressure of a surface within the wound supply of weft or filling when such supply is substantially exhausted. 20
- 35 9. A feeler-motion for looms comprising a feeler-member and an actuator operatively combined, a carrier for said parts mounted to swing around a pivot, and a controller adapted to be actuated by the said actuator, also mounted to swing around a pivot substantially in parallelism with said carrier. 40
10. A feeler-motion for looms comprising a horizontally-arranged carrier-arm or lever, a combined feeler-member and actuator movably mounted upon said carrier-arm or lever, said feeler-member receiving the direct push of the wound mass of weft or filling contained in the working shuttle, whereby the carrier-arm or lever and connected parts are moved forward, and said feeler-member adapted to be displaced longitudinally of the shuttle by the forward pressure when the said mass is substantially exhausted, whereby the actuator is operatively positioned, and a controller actuated by the forward movement of the operatively positioned actuator, said controller constituted by a horizontally-swinging arm or lever substantially parallel with the carrier-arm or lever. 45
11. A feeler-motion for looms comprising a feeler-member having a tip or feeling portion with single projection that receives directly the push of the wound mass of weft or filling contained in the working shuttle to move the feeler-member forward, said feeler-member constructed to be displaced longitudinally of the shuttle by the forward pressure against the end of said projection when the wound mass is substantially exhausted. 55
12. A feeler-motion for looms comprising a feeler-member having a tip or feeling portion with single V-edge projection that receives directly the push of the wound mass of weft or filling contained in the working shuttle to move the feeler-member forward, said feeler-member constructed to be displaced longitudinally of the shuttle by the forward pressure against the V-edge when the wound mass is substantially exhausted. 60
13. A feeler-motion for looms comprising a feeler-member having a tip or feeling end shaped to penetrate between the last coils or turns of weft or filling contained in the shuttle, said feeler-member arranged to be moved forward bodily by the push of the wound mass of said weft or filling against said tip or feeling end and to be 75 displaced longitudinally of the shuttle by the forward pressure when the wound weft or filling is substantially spent, and a support for said feeler-member mounted to cause the displaced projection to "pick 80 under" the adjacent coils or turns. 85
14. A feeler-motion for looms comprising a feeler-member having a tip or feeling end shaped to penetrate between the last coils or turns of weft or filling contained in the shuttle, said feeler-member arranged to be moved forward bodily by the push of the wound mass of weft or filling against the tip or feeling end and to be displaced longitudinally of the shuttle by the forward pressure of a surface within the wound weft or filling when the latter is substantially spent, and a supporting arm or lever swinging around a center located to produce travel of the said tip or feeling end in a flat arc which will cause it to "pick under" the adjacent coils or turns. 90 100
